United States Patent Office.

GEORGE D. SANFORD, OF PEEKSKILL, NEW YORK.

Letters Patent No. 96,485, dated November 2, 1869; antedated May 2, 1869.

IMPROVEMENT IN COAL-STOVES.

The Schedule referred to in these Letters Patent and making part of the same.

To all whom it may concern:

Be it known that I, GEORGE D. SANFORD, of Peekskill, in the State of New York, have invented a certain new and useful Improvement in Stoves; and do hereby declare the following to be a full, clear, and exact description thereof, reference being had to the drawing accompanying this specification, of which—

Figure 1 is a front view of a section of the cylindrical part of a stove containing my improvement;

Figure 2 is a vertical cross-section, taken through the line $x-x$ of fig. 1; and

Figure 3 is a longitudinal cross-section, taken through the line $y-y$.

This invention relates to the better securing of the frames or doors, containing isinglass or other filling, to the body of the stove.

These frames, being made to attach or detach easily, for the purpose of renewing the filling, for repairs, or cleaning parts of the stove, have heretofore been attached either very firmly by some of the usual means of fixed fastening, in which case it was tedious and troublesome to release the frames when desired, or were attached in a simple manner, so as to become quickly detached. But with the latter mode these doors were apt to fall off by things coming into contact with them, or in the moving round or jar of the stove.

Now, by means of my invention, I obtain a frame easily removable, which, at the same time, is not

liable to become detached from accidental causes, as above referred to.

My improvement is constructed and operated as follows:

A is a portion of the cylindrical surface of the stove.

B, the opening, which is covered by the frame C, containing isinglass, or other suitable filling.

On each side of this frame is cast a projection, D, which is hooked at E on opposite sides; the face of each opening against which the frame is placed, is cut away in the form of a notch; such notch at from about two-thirds of its length, up at F toward the top, being again recessed back, which will permit of these hooks passing entirely back of the cylindrical surface of the stove when the frame is raised to such point, and then, when lowered, the hooks take against the edge of the portion of the notch that is not recessed so far back, and thus prevent the frame, if rattled, or even pushed up some distance, from disengaging from the body of the stove.

What I claim as new, and desire to secure by Letters Patent, as my improvement, is—

The construction and arrangement of notches and hooks on the adjustable frame and body of a stove, substantially as and for the purpose described.

GEO. D. SANFORD.
